ASSEMBLER SLIDE RETURN

David Diamond, Forest Hills, N. Y.

Application May 5, 1950, Serial No. 160,341

11 Claims. (Cl. 199—30)

1

This invention relates to typesetting machines and, more particularly, pertains to an improvement in a matrix assembling mechanism.

In present day typesetting machines an assembler slide to which selected matrices are delivered is advanced against the action of a slide return spring toward an assembling elevator by engagement of an assembler star with the endmost matrix or spacer on the slide. Movement of the slide is under control of an assembler slide brake, a device of such construction that, when effective, it is supposed to permit movement of the slide in one direction only, to wit toward the elevator. When the elevator approaches its delivery position it shifts a brake operating lever to render the brake ineffective whereupon the slide is freed for movement in a retrograde direction under the action of the slide return spring.

A major difficulty with this arrangement is that the retrogressive force exerted by the return spring and cancelled when the brake is effective becomes operative when the brake is slightly worn or not properly adjusted. At such time the bias of the return spring is balanced against the intermittent pressure effected by the star wheel paddles, thus causing longitudinal jiggling or vibration of the assembler slide. The vibration is disconcerting to an operator and sometimes causes transposition of matrices. Such vibration is aggravated as the slide fills up and increases the tension on the return spring.

A secondary trouble inherent in the foregoing arrangement is that the assembler slide does not always initiate its cycle at a correct starting position either because the brake is bad and permits the slide to bounce, or because of dust lodged in the machine. As such times one or more of the first matrices delivered may fall off the slide.

It is the primary object of my invention to provide an improved assembler slide return which will eliminate these drawbacks.

It is another object of my invention to provide a positive return for the assembler slide.

It is another object of my invention to provide an improved return of the character described which can be incorporated readily and easily in present typesetting machines.

It is another object of my invention to provide an improved return of the character described which is rugged and comparatively inexpensive to manufacture.

Other objects of this invention will in part

2

be obvious and in part will be pointed out hereinafter.

The invention accordingly consists in the features of construction, combinations of elements, and arrangements of parts, which will be exemplified in the construction hereinafter described, and of which the scope of application will be indicated in the appended claims.

In the accompanying drawings, in which is shown one of the various possible embodiments of the invention,

Fig. 1 is a fragmentary front view of the assembling mechanism of a typesetting machine having an assembler slide return constructed in accordance with my invention, the machine being illustrated at the start of the assembler slide cycle;

Figs. 2 and 3 are sectional views taken substantially along the lines 2—2 and 3—3 respectively of Fig. 1;

Fig. 4 is an enlarged sectional view taken substantially along the line 4—4 of Fig. 1;

Fig. 5 is a sectional view taken substantially along the line 5—5 of Fig. 4;

Fig. 6 is a view taken substantially along the line 6—6 of Fig. 5;

Fig. 7 is a sectional view taken substantially along the line 7—7 of Fig. 1;

Fig. 8 is a sectional view taken substantially along the line 8—8 of Fig. 7;

Fig. 9 is an enlarged fragmentary view taken substantially along the line 9—9 of Fig. 8;

Fig. 10 is a sectional view taken substantially along the line 10—10 of Fig. 8;

Fig. 11 is a front view of the portions of the typesetting machine in the vicinity of the assembler elevator, the latter being illustrated in its raised position; and

Figs. 12 and 13 are enlarged sectional views taken substantially along the lines 12—12 and 13—13 respectively of Fig. 11, these views corresponding to Figs. 9 and 10, respectively.

Referring now in detail to the drawings, the reference numeral 20 denotes the assembling mechanism of a typesetting machine in which there is incorporated a slide return embodying my invention. Said mechanism includes an assembling frame 22 on which the various operative parts are mounted. Matrices 24 deposited on a belt 26 trained about a pulley 28 are delivered to a chute 30 from whence they descend under gravity to a horizontally reciprocable assembler slide 32. The matrices are erected and urged toward a stop 34 at an end of the slide by a star wheel 36.

Said slide traverses an elevator shaft constituting a pair of posts 38, 40 on which an elevator 41 is guided for vertical movement. The elevator is powered in any fashion well known to the art, as by a hand lever or foot treadle (not shown) through a link 41a so that the elevator can be raised when desired by the operator and subsequently lowered.

The mechanism as thus far described is entirely conventional.

Pursuant to my invention the slide return includes an element which is mounted for movement parallel to the elevator, i. e. vertically, a kinematic mechanism positively interconnecting the slide and the element so that movement of the slide as it receives matrices will cause movement of the element, and reverse movement of the element will restore the slide to starting position, and a kinematic mechanism impositively connecting the elevator and element in such manner that the elevator will move the element only when the elevator descends to positively return the slide to starting position and to exert such restoring force only when the elevator is being lowered.

More specifically the element referred to constitutes a bar 42 captively slideable in a track member 44 secured to a block 46. Said block is designed to be mounted on the elevator post 40, as by screws 48, in such position that the element is reciprocable vertically and, therefore, parallel to the path of movement of the elevator. One edge of the bar is provided with a rack gear 50 which meshes with a pinion 52 fixed to a horizontal shaft 54. The shaft is journaled in said block 46 and has fixed to it a second pinion 56 disposed adjacent the path of travel of the bottom edge of the slide. This edge of the slide is provided with a rack gear 58 formed as by securing such a gear thereto or by shaping a portion of the bottom edge of the slide into the desired shape. The gear 58 is in mesh with the second pinion 56 so that when the slide moves in a matrix-accepting direction it will raise the bar 42 and when the bar is driven downwardly it will shift the slide retrogradely.

The second pinion 56 affords one point of support for the slide. Another point of support is provided by a brake 60. Although the brake may be of conventional construction such as now is used, which permits movement of the slide only in a matrix-accepting direction when the brake is effective and in either direction when the brake is open, I prefer to employ a drag brake which permits movement of the slide in either direction against a friction drag when the brake is effective and free movement of the slide in either direction when the brake is open. Said brake includes a fixed shoe 62 and a movable shoe 64. One shoe, e. g. the shoe 62, engages the upper edge of the slide and the other the bottom edge. Said shoes are made of friction material, for example, leather. The fixed shoe is secured to a bracket 66 mounted on the frame 22. The movable shoe is secured to a backing plate 68 which carries a pair of guide pins 70 and a headed stud 72. Said guide pins slide in vertical sleeves 74 mounted on a flange 76, thus ensuring vertical movement of the backing plate 68. Compression springs 78 encircling the guide pins between the backing plate and flange serve to bias the movable shoe against the slide. The sleeves are threaded in the flange so as to enable the friction drag of the brake to be adjusted.

Means is included to cancel the action of the 75

brake. Said means comprises a plate 80 which normally lies flat against the undersurface of the flange 76. The stud freely passes through an opening in the plate and the head of the stud supports the plate in its said position, there being sufficient clearance to allow the brake to function. A pin 82 depending from the flange 76 extends through another opening in the plate, fitting sloppily therein in order to retain the plate in the plan position shown in Fig. 6, and yet to permit rocking thereof about the edge 84. The plate projects beyond the flange to form an operating finger 86 from which a slender abutment 88 extends upwardly. The normal, brake-effective position of the plate 80 is shown in full lines in Fig. 5. If the plate is rocked to the dot-and-dash line positions illustrated in said figure, the stud 72 will pull the movable shoe 64 down against the action of the compression springs 78 thereby opening the brake.

This action is effected by a brake operating lever 90 which is a standard part of a conventional typesetting machine. The operating lever pivots on a screw 92 set in the assembling frame 25 22. An arched leaf spring 94 bears against the back of the operating lever to hold the same frictionally in any set position. One end 96 of the operating lever is located a short distance above the top of the abutment when said lever is in its 30 idle position shown in Fig. 1. At such time the opposite end 98 of the operating lever is engaged by a brake-setting shoulder 100 on an edge of the elevator near the top thereof. A brake-releasing shoulder 102 is located near the bottom of the elevator. The two shoulders are so disposed that one or the other will engage the end 98 of the brake operating lever near the upper and lower limits of travel thereof. When the elevator is raised, the shoulder 102 will, near the end of the movement, press against the lever and oscillate it through a short arc in a clockwise direction as viewed in Fig. 1, thus depressing the lever end 96 and releasing, i. e. opening, the brake. The brake will be held open by the leaf spring 94 until the shoulder 100, near the end of downward movement of the elevator engages the lever to raise the end 96 and set the brake. The brake will remain set until the shoulder 102 again contacts the operating lever.

The impositive kinematic mechanism hereinabove mentioned includes a block 104 fastened to the elevator 41 near the bottom end, as by screws 106, which also secure a retainer 108 against the block. The block and retainer form a non-circular track 110 in which the shank 112 of a bolt 114 is captively slideable, said shank having a cross-section which matches that of the track. A detent finger 116 projects from one end of the bolt and a spring anchoring finger 118 projects from the other end. A helical spring 120 tensed between the finger 118 and a post 122 on the retainer biases the detent finger 116 toward the bar 42. For reasons which will shortly be apparent, the underside of the detent finger is formed with a chamfer 124 and the outer side of said finger has a vertical slot 126. The detent finger is held in its retracted position shown in Fig. 9 by a catch 128 mounted at the free end of a cantilever leaf spring 130. It will be appreciated that depressing the catch will permit the detent to snap to its extended position shown in Fig. 12. This movement of the catch is accomplished by a pin 132 fixed to the upper end of the block 46. Said pin is disposed in the path of

travel of the catch and is engaged thereby at the upper limit of travel of the elevator. The slot 126 prevents the pin from contacting the detent finger in the latter's extended position (see Fig. 13).

The last-named kinematic mechanism also includes an arm 134 rigidly secured to the bar 42 and an edge cam 136 affixed to the block 46. The arm 134 is in the path of travel of the detent finger when the latter is in extended position, and is clear of the path of travel of the catch and of the retracted detent finger. The position of the arm with respect to the longitudinal axis of the bar is such that the arm is below the pin 132 when the slide is in its maximum matrix-accepting position (see Fig. 12). By properly proportioning the pinions 52, 56 the extent of movement of the bar 42 is made less than the vertical throw of the elevator and the arm further is so positioned that at the start of a matrix-accepting cycle said arm is above the detent finger. The arm extends through and is slidable in a slot 137 in the track member 44.

The edge cam is disposed in the path of movement of the extended detent finger and is clear of the catch 128 (see Fig. 10). Said cam is shaped to engage the chamfer 124 on the detent finger near the end of the downward movement of the elevator and to force the bolt 114 retrogradely sufficiently to permit the catch to spring back into its detaining position, this latter occurring slightly after the slide is restored to its starting point.

In the operation of the assembling mechanism, at the initiation of a matrix accepting cycle the several parts are disposed as follows:

The slide 32 is at its starting point, the extreme right as viewed in Fig. 1. The shoulder 100 rests against the brake operating lever 90 so that the brake is effective. The bar 42 and arm 134 are in their lowermost positions. The detent finger 116 is maintained retracted by the catch 128 and is below the arm 134 and cam 136.

As matrices are fed down the chute 30 they are erected by the star wheel 36 and pushed toward the stop 34, thus advancing the slide against the drag of the brake 60 toward the left as seen in Fig. 1. It is to be observed that as the slide travels there is no restoring force, and, hence no vibration of the slide. While the slide is moving during acceptance of matrices, the racks 50, 58 and pinions 52, 56 raise the bar 42.

At some point, determined by the operator, feeding of the matrices will be stopped and the elevator 41 raised. The maximum travel of the slide and bar are inherently limited by the capacity of the typesetting machine and are such that the limit of upward movement of the arm 134 is below the pin 132.

As the elevator is lifted it first will disengage the shoulder 100 from the brake operating lever 90 although this does not affect operation of the brake since the lever is maintained in position by the arched spring 94. Upon further upward movement of the elevator the retracted detent finger will pass the cam 136 and then the arm 134. Near the upper limit of travel of the elevator the shoulder 102 will strike the brake lever thereby to release, i. e. nullify, the brake. At about the same time the catch 128 will strike and be depressed by the pin 132 allowing the detent finger to snap to extended position.

In normal operation of the typesetting machine, the elevator next is lowered. During this period the extended detent will encounter and force down the arm 134, thus moving the slide

back toward its starting point. As the arm nears a position corresponding to the starting point of the slide, the chamfer 124 on the detent finger engages and rides down the cam 136 gradually disengaging said finger from the arm 134. The cam is so shaped and disposed that the arm will be cleared by the detent finger at the instant the slide is brought back to its starting point. Further downward movement of the elevator allows the cam to press the detent finger back far enough to enable the catch to spring up to detaining position. Finally the shoulder 100 engages the brake lever so as to reset the brake which was off during downward travel of the elevator. It will be observed that the slide is restored to starting position smoothly and positively thus preventing bounce and brushing aside any foreign matter.

It may be mentioned that releasing the brake for return of the slide minimizes the requisite slide restoring force which in a conventional machine simply will be the weight of the elevator and parts movable therewith.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein described or shown in the accompanying drawings is to be interpreted as illustrative and not in a limiting sense.

35 Having thus described my invention, I claim
as new and desire to secure by Letters Patent:

1. For use in a typesetting machine including a reciprocable assembler slide and a reciprocable elevator, a slide return comprising an element, 40 means to mount said element for movement parallel to the elevator, a kinematic mechanism for causing movement of the slide as it receives matrices to move the element and reverse movement of the element to restore the slide to starting position, and a kinematic mechanism im- 45 positively connecting the element and elevator for causing the elevator to move the element only when the elevator descends and thereby to return the slide to starting position.

50 2. For use in a typesetting machine including a reciprocable assembler slide and a reciprocable elevator, a slide return comprising an element, means to mount said element for movement parallel to the elevator, a kinematic mechanism for 55 causing movement of the slide as it receives matrices to move the element and reverse movement of the element to restore the slide to starting position, a kinematic mechanism impositively connecting the element and elevator for causing 60 the elevator to move the element only when the elevator descends and thereby to return the slide to starting position, and a drag brake operative on the slide.

3. For use in a typesetting machine including
65 a reciprocable assembler slide and a reciprocable
elevator, a slide return comprising an element,
means to mount said element for movement par-
allel to the elevator, a kinematic mechanism for
causing movement of the slide as it receives mat-
rices to move the element and reverse movement
70 of the element to restore the slide to starting
position, a member movable with said element,
and a member movable with said elevator, said
members being kinematically non-cooperable on
75 rising movement of the elevator, and means to

interengage said members on descending movement of the elevator.

4. For use in a typesetting machine including a reciprocable assembler slide and a reciprocable elevator, a slide return comprising an element, means to mount said element for movement parallel to the elevator, a rack gear and pinion means for causing movement of the slide as it receives matrices to move the element and reverse movement of the element to restore the slide to starting position, and a kinematic mechanism positively connecting the element and elevator for causing the elevator to move the element only when the elevator descends and thereby to return the slide to starting position.

5. For use in a typesetting machine including a reciprocable assembler slide and a reciprocable elevator, a slide return comprising an element, means to mount said element for movement parallel to the elevator, a rack gear movable with the slide, pinion means meshing with the rack gear, a rack gear movable with the element and meshing with the pinion means, a member movable with said element, and a member movable with said elevator, said members being kinematically non-cooperable on rising movement of the elevator and means to interengage said members on descending movement of the elevator.

6. For use in a typesetting machine including a reciprocable assembler slide and a reciprocable elevator, a slide return comprising an element, means to mount said element for movement parallel to the elevator, a kinematic mechanism for causing movement of the slide as it receives matrices to move the element and reverse movement of the element to restore the slide to starting position, a member movable with said element, a member movable with said elevator, means to render said members kinematically non-cooperable on rising movement of the elevator, and means to interengage said members on descending movement of the elevator.

7. For use in a typesetting machine including a reciprocable assembler slide and a reciprocable elevator, a slide return comprising an element, means to mount said element for movement parallel to the elevator, a kinematic mechanism for causing movement of the slide as it receives matrices to move the element and reverse movement of the element to restore the slide to starting position, a member movable with said element, a member movable with said elevator, means to mount one of said members for movement between a position in which it is kinematically non-cooperable with the other member and a position in which it is kinematically cooperable with the other member, means to shift said one member to its first-named position preparatory to rising movement of the elevator, and means to shift said one member to its second-named position preparatory to descending movement of the elevator.

8. For use in a typesetting machine including a reciprocable assembler slide and a reciprocable elevator, a slide return comprising an element, means to mount said element for movement parallel to the elevator, a kinematic mechanism for causing movement of the slide as it receives matrices to move the element and reverse movement of the element to restore the slide to starting position, an arm movable with said element, a detent finger movable with said elevator, means to mount said finger for movement between a position in which it is clear of the path of travel of the arm and a position in which it is in the

path of travel of the arm, spring means to bias the finger to its second-named position, a catch movable with the elevator, spring means to bias the catch to a position at which it detains the detent finger in its first-named position, the path of travel of the finger extending beyond both ends of the path of travel of the arm, a stationary pin above the upper limit of the path of travel of the arm, said pin being in the path of travel of the catch and engageable therewith to depress the catch and allow the finger to be biased to its second-named position, and a stationary cam in the path of travel of the detent finger and engageable therewith to force said finger to its first-named position when the slide has returned to its starting position.

9. For use in a typesetting machine including a reciprocable assembler slide and a reciprocable elevator, a slide return comprising an element, means to mount said element for movement parallel to the elevator, a rack gear and pinion means for causing movement of the slide as it receives matrices to move the element and reverse movement of the element to restore the slide to starting position, an arm movable with said element, a detent finger movable with said elevator, means to mount said finger for movement between a position in which it is clear of the path of travel of the arm and a position in which it is in the path of travel of the arm, spring means to bias the finger to its second-named position, a catch movable with the elevator, spring means to bias the catch to a position at which it detains the detent finger in its first-named position, the path of travel of the finger extending beyond both ends of the path of travel of the arm, a stationary pin above the upper limit of the path of travel of the arm, said pin being in the path of travel of the catch and engageable therewith to depress the catch and allow the finger to be biased to its second-named position, and a stationary cam in the path of travel of the detent finger and engageable therewith to force said finger to its first-named position when the slide has returned to its starting position.

10. For use in a typesetting machine including a reciprocable assembler slide and a reciprocable elevator, a slide return comprising an element, means to mount said element for movement parallel to the elevator, a rack gear movable with the slide, pinion means meshing with the rack gear, a rack gear movable with the element and meshing with the pinion means, an arm movable with said element, a detent finger movable with said elevator, means to mount said finger for movement between a position in which it is clear of the path of travel of the arm and a position in which it is in the path of travel of the arm, spring means to bias the finger to its second-named position, a catch movable with the elevator, spring means to bias the catch to a position at which it detains the detent finger in its first-named position, the path of travel of the finger extending beyond both ends of the path of travel of the arm, a stationary pin above the upper limit of the path of travel of the arm, said pin being in the path of travel of the catch and engageable therewith to depress the catch and allow the finger to be biased to its second-named position, and a stationary cam in the path of travel of the detent finger and engageable therewith to force said finger to its first-named position when the slide has returned to its starting position.

11. For use in a typesetting machine including a reciprocable assembler slide and a reciprocable

elevator, a slide return comprising an element, means to mount said element for movement parallel to the elevator, a rack gear movable with the slide, pinion means meshing with the rack gear, a rack gear movable with the element and meshing with the pinion means, an arm movable with said element, a detent finger movable with said elevator, means to mount said finger for movement between a position in which it is clear of the path of travel of the arm and a position in which it is in the path of travel of the arm, spring means to bias the finger to its second-named position, a catch movable with the elevator, spring means to bias the catch to a position at which it detains the detent finger in its first-named position, the path of travel of the finger extending beyond both ends of the path of travel of the arm, a stationary pin above the upper limit of the path of travel of the arm, said pin being in the path

of travel of the catch and engageable therewith to depress the catch and allow the finger to be biased to its second-named position, a stationary cam in the path of travel of the detent finger and engageable therewith to force said finger to its first-named position when the slide has returned to its starting position, and a drag brake operative on the slide.

DAVID DIAMOND.
